COLUMBIA PLANOGRAPH CO., WASHINGTON, D. C.

UNITED STATES PATENT OFFICE.

EDWARD L. TATUM, OF SHOP SPRING, TENNESSEE.

HAY-PRESS.

1,073,304.

Specification of Letters Patent. Patented Sept. 16, 1913.

Application filed January 11, 1912. Serial No. 670,668.

To all whom it may concern:

Be it known that I, EDWARD L. TATUM, a citizen of the United States, residing at Shop Spring, in the county of Wilson and State of Tennessee, have invented certain new and useful Improvements in Hay-Presses; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to certain new and useful improvements in baling presses; and my invention has for its object to improve the construction and operation of that class of baling presses in which a tamping member is employed which enters the hopper opening from above, and is actuated through the movement of the plunger, as will be more fully described herewith and finally pointed out in the claim.

In the accompanying drawings forming a part of this specification: Figure 1 is a vertical central sectional view of a baling press constructed according to my invention. Fig. 2, shows a detached detail of the tamping mechanism.

In carrying out the main object of my invention I employ an open-ended housing including the bottom 3, the sides A, and the base sills 2, 2, to which the bottom 3 is secured. Extending transversely across the upper portion of the housing are the brace bars 4, 5, 6, 7, and 8 secured to the sides A in any suitable manner.

As shown in Fig. 1, the brace bars 4, 5, and 6, give support to the top 10, while the brace bars 7, and 8, give support to the top 12, which is in the form of two boards held in paralleled spaced relation, so as to provide an access opening between these two top boards or members 12. Near one end the housing is provided with a crank shaft B, which has secured to it a gear wheel D, while held within the sides A, above the crank shaft B is the driving shaft F, held in place by means of the bearing 13. This shaft F, is brought in connection with any suitable driving power and is provided with a pinion E, meshing with the gear D.

Slidably held within the housing, is the hollow plunger 14, having the extending top H. As shown, this plunger is provided with an eye bolt 15, carrying a pin 16, upon which is pivotally held the end of the pitman I, which has its remaining end secured to the crank of the shaft B, as shown in Fig. 1. As disclosed a feed opening k, is provided between the bars 6 and 7.

Secured to the transverse bar 5, by means of the hinge J, is the lever O. As shown this lever is of such a length that it terminates at a point above the hopper opening k, the pivot end of the bar being near the discharge end of the baler. Secured to the end of the projection top H, of the plunger by means of the hinge J', is the operating bar N, which has its other end pivotally secured to the lever O, by means of the hinge L.

Extending from the lever O, at its union with the operating bar, is the tamping bar Q, braced by means of the bracket 16'. As shown this tamping bar is arranged to pass through the hopper opening k, while the operating bar N, is arranged to pass through the access opening formed between the top members 12.

The operation of the device is very simple. On the incursion of the plunger 14, the toggle forming members O and N, as well as the tamping member Q are raised. The operator then feeds a suitable amount of material through the hopper opening k. This material on the excursion of the plunger is carried down by means of the tamping member Q, and this tamping motion is of course repeated on each rearward movement of the plunger.

A baling press constructed according to my invention, is both durable, and efficient in operation.

Having thus described my said invention what I claim as new and desire to secure by United States Letters Patent is:—

In a baling press, the combination with an open-ended housing having a discharge end and a central hopper opening within its top, of a lever having one end pivotally secured near the discharge end of said housing with its other end terminating above said hopper opening, a plunger slidably held within said housing, said housing having an access opening within its top above

said plunger, an operating bar pivotally secured at one end to said lever and at its other end to the top of said plunger and passing through said access opening, and a
5 tamping bar secured to the end of said lever arranged at times to pass through said hopper opening.

In testimony whereof I hereunto affix my signature in the presence of two witnesses.

EDWARD L. TATUM.
